UNITED STATES PATENT OFFICE.

BRADLEY A. HARD, OF NEW YORK, N. Y.

DESIGN FOR WRITING-PAPER AND CARDS.

SPECIFICATION forming part of Design No. 14,067, dated July 10, 1883.

Application filed May 25, 1883. Term of patent 14 years.

To all whom it may concern:

Be it known that I, BRADLEY A. HARD, of New York city, county and State of New York, have invented a new and original Design for Writing-Paper and Cards, of which the following is a specification.

The accompanying photograph illustrates my new design for writing-paper and cards.

On the face of the paper are representations of numerous autumn-leaves, that are marked A, B, C, D, D', E, F, G, H, I, J, K, M, N, O, P, and R. The background L, or part of the paper not covered by the leaves above mentioned, and which have more or less definite outlines, is marked with veins in imitation of parts of leaves, so as to give the appearance of the entire paper being covered with leaves that lie in different planes. Thus the leaves A, C, E, D', I, and O appear to be nearest the eye of the observer and to partly overlap some of the other leaves. For example, the leaf A appears to partly overlap the leaf B, the leaf

C appears to partly overlap the leaf J, the leaf E appears to partly overlap the leaf D, the leaf D' appears to partly overlap the leaf F, the leaf I appears to partly overlap the leaves G and M, and the leaf O appears to partly overlap the leaves N and K. The remaining leaves, B, D, F, G, H, J, K, M, N, P, and R, being partly covered by other leaves, are therefore apparently in a plane farther away from the eye of the observer than the leaves A, C, E, D', I, and O, and the background L seems to be still farther away from the eye of the observer, thus producing a peculiar effect upon the eye.

I claim—

The design for paper or cards, consisting of the representations of leaves in different planes, substantially as shown.

BRADLEY A. HARD.
